United States Patent Office.

JULIUS BEVINS, OF UNADILLA FORKS, NEW YORK.

Letters Patent No. 70,394, dated November 5, 1867.

IMPROVEMENT IN DEVICE FOR HOLDING SAP-BUCKETS.

The Schedule referred to in these Letters Patent and making part of the same.

TO ALL WHOM IT MAY CONCERN:

Be it known that I, JULIUS BEVINS, of Unadilla Forks, in the county of Otsego, and State of New York, have invented a new and improved Bracket or Device for Holding Sap-Buckets to Sugar-Trees; and I do hereby declare that the following is a full and exact description thereof, reference being had to the accompanying drawings, and to the letters of reference marked thereon.

The nature of my invention consists in providing a peculiarly-shaped bracket, which is fastened to the sugar-tree, and so arranged that it will hold or support the sap-bucket in an upright position.

To enable others skilled in the art to make and use my invention, I will proceed to describe its construction and operation, reference being had to the drawings, in which the same letters indicate similar parts in each of the figures.

Figure 1 is a side view of the device, and

Figure 2 is a front view of the parts of the same with the sap-bucket in its proper position.

In the accompanying drawings, A is the main bar of the bracket, which may be made of wood, iron, or any other suitable material. It has a hole near its upper part, through which the nail G is driven, which fastens or secures it to the sugar-tree. The bracket is designed to bear against the tree at its upper part, while the lower part extends outward sufficiently to receive the bottom or chime of the bucket or sap-pail, and to hold it, as shown in fig. 1, in its upright position. The bracket A, fig. 2, is also provided with a hook, B, which serves to hold the top or highest end of the stave of the pail E; also, a curved hook, C, at its lowest part, which is fitted to receive the bottom of the pail E. The curved hook C may be firmly or removably set on the bar A, and may be made of various shapes to hold the bottom of sap-buckets and pails of the various forms now in use. The bracket, when it is set on the sugar-tree at the commencement of the boiling season, is not required to be removed until the close of said time, but the sap-bucket, by being raised up behind the hook B, will be released from the curved hook C, and be thus disengaged or loosened from the same.

Having thus fully described my invention, I will now state what I desire to secure by Letters Patent, to wit: I claim the bar A, the hook B, and the curved hook C, when they are arranged in the manner specified.
